(57) **CLAIM**

The ornamental design for a ceiling fan with light, as shown and described.

DESCRIPTION

FIG. 1 is a rear, left and bottom perspective view of a ceiling fan with light, showing my new design;

FIG. 2 is a front, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the ceiling fan with light that form no part of the claimed design.

The break lines on the blades of the ceiling fan with light depict a symbolic break in length and form no part of the claimed design.
